UNITED STATES PATENT OFFICE

RAYMOND L. CARR, OF BOSTON, MASSACHUSETTS

DESIGN FOR A COMBINED VEHICLE HOOD AND RADIATOR SHELL OR SIMILAR ARTICLE

Application filed August 10, 1932. Serial No. 44,573. Term of patent 14 years.

To all whom it may concern:

Be it known that I, RAYMOND L. CARR, a citizen of the United States of America, residing at Boston, in the county of Suffolk and Commonwealth of Massachusetts, have invented a new, original, and ornamental Design for a Combined Vehicle Hood and Radiator Shell or Similar Article, of which the following is a specification, reference being had to the accompanying drawings, forming a part thereof.

Fig. 1 is a top plan view of the combined

vehicle hood and radiator shell embodying my new design;

Fig. 2 is a side elevation thereof;

Fig. 3 is a front elevation thereof.

I claim:

The ornamental design for a combined vehicle hood and radiator shell or similar article substantially as shown.

Signed by me at Boston, in the county of Suffolk and Commonwealth of Massachusetts, this 9th day of August, 1932.

RAYMOND L. CARR,
